LOOSE LEAF BINDER

Erik L. Krag, Chicago, Ill., assignor of one-tenth
to E. J. Andrews, Chicago, Ill.

Application August 23, 1930, Serial No. 477,290

13 Claims. (Cl. 129—13)

This invention relates to loose-leaf binders, and it has for its object providing improved means for opening and closing the binder backs when it is desired to change the leaves of the binder. Particular objects of the invention are providing means for operating the binder backs which are convenient and effective and which require a minimum of force to operate; and also to provide means which can be locked conveniently in any position of the binder backs.

Of the accompanying drawing, Fig. 1 is a sectional view of the binder back along the line 7—7 of Fig. 2, but showing the racks in outward positions, which embodies features of my invention; Fig. 2 is a reduced plan view of the bottom of the back with the bottom cover and the rack boxes removed; Fig. 3 shows means for operating the mechanism of the binder back; Fig. 4 shows a modification of the operating means; Fig. 5 is a modification of the binder back, represented by a transverse sectional view along the line 5—5 of Fig. 6; and Fig. 6 is a reduced plan view of the binder of Fig. 5 with the gear cover removed.

As is well understood, loose-leaf binders are in common use which consist of binder backs having prongs 40 for supporting the loose-leaves by passing through openings in the edges of the leaves; and the leaves may be removed or other leaves attached by separating the prongs until the ends of the prongs are spaced apart a sufficient distance to remove the leaves from one set of prongs to the other.

Loose-leaf binders of this nature are often large and heavy and more or less cumbersome to handle, and it is at times difficult to properly separate the prong plates as there is a tendency for the sides of the binders and the loose-leaves thereof to interfere more or less with the proper separating of the plates. To obviate this, I have provided the improved means illustrated herein, which consists of a rack 41 which is fixed with reference to each of the prong plate holders 14. These racks are connected either directly to the plates or to mechanism which supports the plates. In this instance, I have shown each of the racks 41 attached to a plate 14 in which the prong plates 13 are mounted for longitudinal movement. But it is to be understood that my invention is not limited to binders in which the prong plates are longitudinally movable.

The racks are slidably mounted in the frame or casing 12 and are operated by means of pinions 44. Obviously, as these pinions are rotated, the racks will be moved transversely, either in-

wardly or outwardly, carrying with them the prong plates to which the racks are directly or indirectly connected.

In this instance, the prong plates 13 are slidably mounted longitudinally in the guide plates 14, so that the prongs in one plate may be moved with reference to the prongs in the other plate, as is common, in order to shift the leaves from one position in the binder to another position, by shifting from one set of prongs to another set.

The curved prongs 40 are operated by curved racks 41, the racks being guided in curved boxes 42. I prefer, in this instance, to have three pairs of pinions 44 with the pinions near the ends of the shafts 43 operating the racks but being spaced apart so as not to mesh with each other. The shafts are operatively connected, by means of the inner pinions 44, one fixed to each shaft, and the pinions meshing with each other.

Also, in this instance, I prefer to have yielding means tending to keep the binder closed, as the weight of the paper and backs tend to force the binder open. The yielding means which I prefer comprises a spring 45 mounted on one of the shafts and with one end fixed to the casing, in any suitable manner, and the other end fixed to the shaft. The spring is so set that it has a tendency at all times to force the binder to its closed position.

Also, with this type of binder, I prefer to have a form of operating handle which comprises an arm 50 fixed to one of the shafts 43 and co-acting with the toothed segment 51, by means of a slidably mounted finger 52. The segment is fixed to the casing of the binder back. A spring 53 at all times forces the finger into coaction with the teeth and, as a consequence, the mechanism tends to hold the binder sides in any position. The handle 54 is used for operating the arm 50 and for forcing the finger out of coaction with the teeth when it is desired to operate the mechanism.

A modification of the operating handle comprises an arm 55 in which is slidably mounted a handle 56 to which is connected, by any suitable means, a latch 57 adapted to coact with a ratchet 58 fixed to the casing. A compression spring 59 at all times forces the latch into coaction with the ratchet teeth, and the handle 56, being slidably mounted in the arm, is adapted to force the latch away from coaction with the teeth.

This latter type of operating handle is desirable for use with the curved prong binder of Fig. 1, with or without the spring 45, but it is particularly applicable when the spring is omitted.

as it at all times holds the binder from opening further when the handle is released, and firmly locks the binder in its closed position.

5 A stop 26 is fixed to the frame which limits the opening of the binder by coacting with the arm 50 as it is operated to open the binder.

A modification of the binder back is illustrated in Fig. 5, which is somewhat similar to the binder back of Fig. 1, except that it has the 10 arch prongs 65 fixed to horizontal plates 66, which are slidably mounted on plates 67. The plates 67 are fixed to the ends 68 of rack bars 69. These rack bar ends are mounted beneath the plates 66 and 67 as indicated and above the plate 15 70, to which is attached the back 71 of the binder. The racks are operated by means of pinions 72, which are arranged preferably similar to the arrangement of Fig. 2. The racks are mounted in boxes 73, so that the racks are suitably supported as they are being operated, and the boxes, 20 as well as the gears and shafts, are mounted in a casing 74, which extends from one end of the binder back to the other, and is fixed to the plate 70 at the ends of the casing and plate.

25 In this embodiment of the invention, the gear operating mechanism is similar to that of the other embodiment, but it is inverted so that the gear wheels are over the racks instead of under them, and are above the plane of the prong plates 66 instead of beneath the plane. The operating handle which I prefer for this modification is similar to that of Fig. 2, but it is to be understood that the type of handle shown in Fig. 4 may be used for operating this or the other 30 form of the binder.

35 I claim as my invention:

1. A loose-leaf binder comprising a casing, 40 means on each side of said casing for holding loose-leaf prongs, means for varying the distance between said holding means, said varying means comprising a pair of shafts rotatably and longitudinally mounted in said casing, a gear rack fixed to each of said holding means, pinions fixed to said shafts and meshing respectively with said racks, means for rotating one of said shafts, operative means connecting said two shafts, said rotating means comprising an arm fixed to said shaft, a stop fixed to said casing, and means on said arm adapted to coact with said 45 stop when said holding means are in their open positions.

50 2. A loose-leaf binder comprising a casing, means on each side of said casing for holding loose-leaf prongs, means for varying the distance between said holding means, said varying means comprising a pair of shafts rotatably and longitudinally mounted in said casing, a gear 55 rack fixed to each of said holding means, pinions fixed to said shafts and meshing respectively with said racks, means for rotating one of said shafts, and operative means connecting said two shafts, said shafts being mounted above the plane in which said holding means lie.

60 3. A loose-leaf binder as claimed in claim 2, 65 in which said rotating means comprises an arm fixed to said shaft, and including means for holding said arm in any adjusted position of said shaft.

70 4. A loose-leaf binder as claimed in claim 2, 75 including means for holding said rotating means in the closed position of said loose-leaf holding means.

5. A loose-leaf binder comprising a casing, 75 means on each side of said casing for holding loose-leaf prongs, means for varying the dis-

tance between said holding means, said varying means comprising a pair of shafts rotatably and longitudinally mounted in said casing, a gear rack fixed to each of said holding means, pinions fixed to said shafts and meshing respectively with said racks, means for rotating one of said shafts, operative means connecting said two shafts, said rotating means comprising an arm fixed to said shaft, and means for holding said arm in any adjusted position of said shaft.

10 6. A loose-leaf binder comprising a casing, means on each side of said casing for holding loose leaves, means for varying the distance between said holding means, said varying means comprising a shaft rotatably and longitudinally 15 mounted in said casing, a gear rack fixed to one of said holding means, a pinion fixed to said shaft and meshing with said rack, means for rotating said shaft, and resilient means fixed to said shaft tending to rotate it in one direction.

20 7. A loose-leaf binder as claimed in claim 6, including means for holding said rotating means in the closed position of said loose-leaf holding means.

25 8. A loose-leaf binder comprising a casing, means on each side of said casing for holding loose-leaf prongs, means for varying the distance between said holding means, said varying means comprising a gear rack fixed with reference to one of said holding means, a pinion 30 mounted in said casing and meshing with said rack, means for rotating said pinion, said rack being curved, and curved prongs mounted on said holding means, and resilient means fixed to said shaft tending to rotate it in one direction.

35 9. A loose-leaf binder comprising a frame, spaced means mounted on said frame for holding loose-leaf prongs; means for varying the distance between said spaced means, said varying means comprising a shaft rotatably mounted in said frame, means operatively connecting said shaft with one of said spaced holding means, means for rotating said shaft, said rotating means comprising an arm fixed to the shaft, and 40 means for holding said arm in adjusted positions, said latter means comprising a toothed segment fixed to the frame and a pawl movably mounted on the arm arranged to coact with the segment.

50 10. A loose-leaf binder comprising a casing, means on each side of said casing for holding loose-leaf prongs, means for varying the distance between said holding means, said varying means comprising a pair of shafts rotatably and longitudinally mounted in said casing, a gear rack fixed to each of said holding means, pinions fixed to said shafts and meshing respectively with said racks, means for rotating one of said shafts, and operative means connecting said two shafts, said shafts being mounted above the plane in which said holding means lie.

55 11. A loose-leaf binder comprising a casing, means including guide plates on each side of said casing for holding loose-leaf prongs, means for varying the distance between said holding means, said varying means comprising a pair of shafts rotatably and longitudinally mounted in said casing, gear racks each fixed at one end to a respective guide plate, pinions fixed to said shafts and meshing respectively with said racks, means for rotating one of said shafts, operative means connecting said two shafts, said shafts being mounted above the plane in which said 60

guide plates lie, horizontal prong plates slidably mounted on said guide plates, and arched prongs fixed to said prong plates and projecting upwardly and inwardly.

5 12. A loose-leaf binder comprising a casing, means on each side of said casing for holding loose-leaf prongs, means for varying the distance between said holding means, said varying means comprising a shaft rotatably mounted in 10 said casing, a gear rack fixed to one of said holding means, a pinion fixed to said shaft and meshing with said rack, means for rotating said shaft comprising an arm fixed to said shaft, a stop fixed to said casing, and means on said

arm adapted to coact with said stop when said holding means are in their open positions.

13. A loose leaf binder comprising a casing, means on each side of the casing for holding loose leaf prongs, means for varying the distance between said holding means, said varying means comprising a shaft rotatably and longitudinally mounted in said casing, a gear rack fixed to one of said holding means, a pinion fixed to said shaft and meshing with the rack, 10 and means for rotating the shaft, said shaft being mounted above the plane in which said holding means lie.
